J. P. HISE

FLASH LIGHT ATTACHMENT FOR GUNS AND OBJECT INDICATORS

Filed Dec. 6, 1923

Patented Sept. 1, 1925.

1,551,742

UNITED STATES PATENT OFFICE.

JOHN PAUL HISE, OF HIGHTOWN, VIRGINIA, ASSIGNOR TO THE HISE GUN FLASH LIGHT COMPANY, OF MARLINTON, WEST VIRGINIA, A CORPORATION OF WEST VIRGINIA.

FLASH-LIGHT ATTACHMENT FOR GUNS AND OBJECT INDICATORS.

Application filed December 6, 1923. Serial No. 678,994.

To all whom it may concern:

Be it known that JOHN PAUL HISE, a citizen of the United States, residing at Hightown, in the county of Highland and State 5 of Virginia, has invented new and useful Improvements in Flash-Light Attachments for Guns and Object Indicators, of which the following is a specification.

It is the purpose of the present invention 10 to provide, in a device of the present character, a construction including means of adjustment to adapt the flashlight for long and short range, both with relation to the diameter of the light area and the angular direction with reference to the gun barrel.

Another purpose is to provide, in a flashlight, a construction for projecting a spotlight, the casing of the flashlight being mounted in a guide tube which includes a 20 lens at its outer end, so constructed that by adjusting the casing of the flashlight, the diameter of the spotlight area may be varied.

Still another purpose is to provide, in a 25 flashlight attachment for guns, means for holding the flashlight casing in different adjusted positions in the guide tube so as to prevent the flashlight casing from movement toward the stock of the gun when the gun is raised closely approximating a perpendicular position.

A further purpose is to provide means for 30 retaining a switch-button depressed to maintain the circuit closed and the flashlight illuminated while the gun is in use, there also being means to permit the switch-button 35 to be released to open the circuit for extinguishing the flashlight.

A still further purpose is the provision of 40 means to be attached to or adjacent any object, preferably on the rear end of the flashlight casing, for the purpose of indicating the location of the object in the dark. This means comprises a stationary member and a 45 rotating member, the former having any suitable wording, such as "Here I am", "Letter box" or automobile "License number" or the like applied thereon in phosphorus or any other suitable material so that it is visible in the dark, the movable plate acting to 50 cover this wording, if desired.

Also it is a further purpose to provide 55 means for securing these members together and including means to secure the members to the object to be located.

It is to be understood that the particulars 55 herein given are in no way limitative and that, while still keeping within the scope of the invention, any desired modifications of detail and desired proportions may be made in the apparatus according to the circumstances. 60

The invention comprises further features and combinations of parts to be hereinafter set forth, shown in the drawings and 65 claimed.

In the drawings:

Figure 1 is a view in side elevation of a gun, showing the improved flashlight attachment embodying the invention applied 70 in an operative position.

Figure 2 is a view partly in elevation and partly in section through the guide tube, showing the flashlight mounted therein with its casing in section, showing the character of lenses carried by the guide tube and the 75 flashlight casing and showing the means for holding the flashlight casing in different positions.

Figure 3 is an enlarged detail perspective view showing how the switch-button for the 80 flashlight may be retained depressed while the flashlight casing is adjusted.

Figure 4 is an enlarged detail view showing 85 how the flashlight casing may be held in different adjusted positions.

Figure 5 is an enlarged view of the device 90 for indicating the location of an object adapted preferably for use on the rear end of the flashlight casing.

Figure 6 is a sectional view through Figure 95 5 on line 6—6 thereof.

Figure 7 is a detail view of a modified form of object indicating means as applied to a depending electric light bulb.

Figure 8 is a detail sectional view of a modified form of object indicating means wherein the inner tube is movable to expose 95 a luminous paint.

Figure 9 is a sectional view on line 9—9 of Figure 8. 100

Referring to the drawings, 1 designates a tubular guide provided with means for attachment to the barrel 2 of a sporting rifle or other firearm and mounted in the guide is a lighting unit or flashlight proper 3 which is removably fitted in place. The flashlight casing may have sliding movement in a direction substantially parallel 105

with the gun barrel for the purpose of varying the diameter of the area of the spotlight projected by the lighting unit. In other words, the forward end of the guide is 5 provided with a lens 4 which is flat on its exterior face and convex on its interior face. The end of the flashlight casing has a lens 5 which is concavo-convex, the convexity of the lens facing the lens of the guide tube 10 while the concavity faces inwardly of the flashlight casing. Obviously, when the flashlight casing is adjusted slidably in the guide, the two lenses cooperate for creating a 15 change in the light rays for the purpose of varying the diameter of the area of the spotlight.

The flashlight casing to the rear of the lens 5 has a distance reflector 6 including an electric light bulb 7, and also mounted in 20 the flashlight casing is a battery 8, the end of which has a yielding tongue 9 controlled by a push-button 10 of which the outer extremity projects beyond the outer surface of the flashlight casing. The tubular guide 25 has an elongated slot 11 in which the push-button 10 engages. One end of the flashlight casing has a terminal knob 12 which aligns with the push-button and also engages through the slot 11. It is possible to 30 grasp the knob 12 and move the flashlight casing longitudinally through the tubular guide for the purpose of positioning the same in order to vary the diameter of the area of the spotlight. One edge of the slot 35 is provided with a plurality of teeth 13 with which the terminal knob may engage for holding the flashlight casing in different positions in the tubular guide, especially when the gun is disposed approximating a 40 perpendicular position.

The opposite edges of the slot at a suitable location between its ends have semi-circular recesses which are, owing to their opposite positions, of a diameter a trifle 45 larger than the head of the push-button 10. In fact, these recesses constitute an opening 14 to permit of the head of the push-button passing therethrough, that is, when the button is depressed. When the button is 50 depressed and the flashlight casing moved longitudinally in the tubular guide so as to dispose the head out of registration with the opening, the yielding tongue 9 will be depressed and its terminal will contact with 55 the base of the electric light bulb and thereby close the circuit and cause the bulb to light. As long as the push-button is held depressed, owing to the inner surface of the guide tube immediately adjacent the slot 60 engaging with the head of the button, the yielding tongue will remain in contact with the base of the electric light bulb.

The battery 8 is mounted in the flashlight casing and by means of a spring 15 one end 65 of the battery is held in contact with an

annular shoulder 16 on the interior of the flashlight casing so that the yielding tongue may be held in a position to engage with the base of the bulb. The tubular guide is flared at its rear end, as shown at 18', to 70 facilitate the introduction of the flashlight casing which, in common with the commercial forms of flashlights, is of tubular construction as shown.

The flashlight may be easily removed from 75 the tubular guide and used independently of the gun for purposes other than locating the object aimed at, when used in connection with the gun.

The tubular guide is provided with front 80 and rear clamps 17 and 18 for engagement and rear clamps 17 and 18 for engagement with the gun barrel and adapted to be secured thereto in embracing relation therewith, as shown, the rear clamp having connection with a supporting block 19 with 85 which is associated an adjusting element, such as a screw 20, which serves as a means of varying the angular position of the guide with relation to the axis of the gun barrel to cause a convergence upon a point at the 90 range of the proposed shot, to the end that the axis of the gun barrel may be directed at about the center of the light area projected by the light unit upon the object at 95 which the barrel is aimed.

In order that the flashlight may be discerned in the dark, either when it is removed from the tubular guide and used separately therefrom or when inserted in the guide, a 100 location indicator 22 is applied to one end of the flashlight casing. This indicator, while preferably used on a flashlight carried by a gun, may be used upon or adjacent any object, either adjacent a push-button, a depending electric light bulb, door knob, 105 the slot in a mail box or adjacent a license number plate on an automobile or close to any object, so that the object is discernible in the dark.

This signal, in its preferred form, 110 comprises two disks 23 and 24 which are riveted together concentrically by means of an eyelet 25. The disk 23 remains substantially stationary while the other disk 24 (which is of segmental shape) is rotatably movable 115 and is provided with diametrically opposite lugs or projections 26 with which the fingers may engage for the purpose of rotating the segmental disk.

The stationary disk has applied to one face 120 thereof, in a circular direction, a sign or indication, such as the words "Here I am", "Letter box", or the like made in phosphorus, so that such indications are discernible in the dark. The surface of the disk containing this design may have a coating of white shellac or varnish or any other suitable material that will adhere to the surface and yet permit the sign to appear through the coating. This coating is 125 130

provided for the purpose of preserving and rendering the sign durable.

The rotating disk has a segmental cut-away portion 27 which conforms to the contour of the sign so that when this cut-away portion is positioned adjacent the sign, the sign is exposed. However, by grasping the lugs or ears 26, the segmental disk may be rotated for the purpose of covering the sign.

10 A nail, screw or other fastening means 28 may pass through the opening in the eyelet for fastening the location indicator to or adjacent any object which will render the object discernible in the dark.

15 Again referring to the flashlight, it will be noted that the tubular guide 1 is substantially as long as the flashlight itself which may be moved a short distance in either direction, which will act to make the light as large or as small as may be desired.

In Figure 7, there is disclosed a modified structure of location indicator which comprises a tube 29 to be mounted upon a cord 30 of an electric light bulb, that is, immediately above the bulb socket. The lower end of this tube, as shown at α in Figure 7, is provided with a band of luminous paint, preferably in the form of a coating of phosphorescent material. It is obvious that the entire circumference of the tube 29 may be provided with a phosphorous or luminous paint coloring. A second tube 31 telescopes the first tube and is provided with a pair of ears 32 which may be grasped for moving 35 the tube 31 to expose the luminous paint or phosphorous coloring in order that the electric light bulb may be located in the dark.

It is obvious that the tube 31 may be mounted stationary and the tube 29 movable without departing from the principle of the modified construction. Upon referring to Figures 8 and 9, it will be seen that such a construction is obvious for the reason that an exterior tubing 31 α is mounted upon the 45 cord immediately above the lamp socket, and arranged interiorly of this tube is a movable tube 29 α . Figure 9 clearly discloses the fact that both tubes 29 α and 31 α are split. However, the inner tube 29 α is provided with a pair of ears 32 α which extend in parallelism between the split edges of the tube 31 α .

The inner tube 29 α is capable of expansion. For instance, by grasping the two ears 32 α , 55 the inner tube may be contracted, allowing

it to be raised so as to expose a luminous paint or phosphorescent coloring which may be made in the form of a band at b adjacent the upper end of the inner tube 29 α . This band b of luminous paint may extend the 60 entire length of the tube 29 α , if desired, so that the greater the exposure, the easier the lamp is discernible. When the ears 32 α are released, the inner tube 29 α expands in contact with the inner surface of the outer tube 65 31 α and holds the inner tube 29 α in different positions due to the friction.

The invention having been set forth, what is claimed is:

1. A flashlight attachment for firearms 70 comprising a tubular guide provided with means for attaching the same to the barrel of a firearm, a lens carried at the outer end of the guide, and a light unit slidably and removably fitted in the guide and having a 75 lens facing the first said lens, said light unit being instantaneously adjustable longitudinally of the guide to increase or decrease the light area projected by said unit.

2. A flashlight attachment for firearms 80 comprising a tubular guide provided with means for attaching the same to the barrel of a firearm, a lens carried at the outer end of the guide, and a light unit slidably and removably fitted in the guide and having a 85 lens facing the first said lens, said light unit being instantaneously adjustable longitudinally of the guide and being provided with a positive locking means to maintain its 90 adjustment.

3. A flashlight attachment for firearms including a tubular guide with means for attaching the same to the barrel of a firearm, a lens at the outer end of the barrel, and a light unit slidably and removably fitted in 95 the guide and having a lens facing the first lens, whereby the adjustment of the unit may increase or decrease the diameter of the spotlight area projected by the unit, the light unit having an exteriorly projecting 100 switch-button, the guide having a longitudinal slot with opposite openings or recesses through which the head of the switch-button may be depressed, whereby the button may ride under the opposite edges of the slot to 105 hold the switch closed.

In testimony whereof he affixes his signature.

JOHN PAUL HISE.
